Patented June 1, 1920.

Inventor.

C. R. Chenery.

By.

A. Hanbury Jr. Attorney.

UNITED STATES PATENT OFFICE.

CHARLES R. CHENERY, OF BUFFALO, NEW YORK.

MILK-BOTTLE.

1,342,013.

Specification of Letters Patent. Patented June 1, 1920.

Application filed May 27, 1919. Serial No. 300,051.

To all whom it may concern:

Be it known that I, CHARLES R. CHENERY, a citizen of the United States, residing at Buffalo, in the county of Erie and State of

5 New York, have invented certain new and useful Improvements in Milk-Bottles; and I do hereby declare the following to be a full, clear, and exact description of the invention, such as will enable others skilled in 10 the art to which it appertains to make and use the same.

My invention relates to improvements in liquid containing receptacles and more particularly to paper milk bottles.

15 An important object of this invention is to provide a paper milk bottle so constructed so as to permit of the utilization of the filling and capping machines now in use for filling and capping my improved paper 20 bottle.

A further object of the invention is to provide a paper milk bottle constructed of a plurality of paper layers having one of its layers terminating short of the top of the 25 other layers thereby providing a cap receiving shoulder.

A further object of this invention is to provide a paper milk bottle having a reinforcing collar embedded within the layers 30 for strengthening the neck of the bottle.

A further object of this invention is to provide a paper milk bottle of the character described having a novelly constructed bottom adapted to reduce to an appreciable extent the cost of manufacturing the bottle.

Other objects and advantages of this invention will be apparent during the course of the following description.

In the accompanying drawing forming a 40 part of this specification and in which like numerals are employed to designate like parts throughout the same.

Figure 1 is a side elevation of a bottle constructed in accordance with my invention, parts thereof being shown in section, and,

Fig. 2 is a vertical section through the same.

In the drawing wherein for the purpose of 50 illustration is shown the preferred embodiment of my invention, the numeral 5 designates the body portion of my improved bottle. The body portion 5 includes inner and outer paper layers 6 and 7 respectively. The 55 layers 6 and 7 are formed of paper wound in opposite directions to supply the desired

degree of rigidity. In constructing the model, the body portion 5 is provided with a reduced upper portion to provide a neck. An inner layer 8 of wax paper or other 60 waterproof material is disposed inwardly of the layer 6 and has its top side terminating short of the tops of the elements 6 and 7, for providing a cap receiving shoulder 10. An annular collar 11 is disposed within the 65 body portion 5 and has its top thereof in horizontal plane with the top of the body portion and has its lower portion extending beyond the upper end of the inner layer 8 for providing a reinforcing element. 70

As clearly shown in Fig. 2, the lower side of the annular collar 11 is tapered.

The lower end of the inner layer 8 terminates short of the bottom of the body portion 5 thereby spacing a bottom 12 from 75 the surface on which the bottom rests. The bottom 12 has its sides 13 extended between the inner layer 8 and body portion 5 and secured thereto by any suitable means. The edge portions 13 function as flanges in supporting the bottom 12. 80

In the use of invention, it will be apparent that the same filling and capping machines may be employed as are now employed in filling and capping the usual glass milk 85 bottles.

While I have shown and described the preferred embodiment of my invention, it is understood that I may make such minor changes in arrangement and construction of 90 parts, as will remain within the spirit of the invention and the scope of the appended claim.

Having thus described my invention, what I claim is:—

95 A receptacle including a plurality of strips wound in tubular formation, a liquid proof sheet disposed upon the inner face of the innermost strip and stopping short of the upper end of the strips, and an annular 100 reinforcing element engaged between the upper ends of the liquid proof sheet and the inner strip and retaining the upper edge of said sheet out of the plane of the reinforcing element to afford a shoulder upon which 105 a closure cap is adapted to seat.

In testimony whereof I affix my signature in presence of two witnesses.

CHARLES R. CHENERY.

Witnesses:

W. J. HEGGEMUND,
N. G. HORITZ.
